UNITED STATES PATENT OFFICE.

JAMES C. FRENCH, OF BROOKLYN, NEW YORK.

DEVICE FOR OPERATING TRAP-DOORS.

SPECIFICATION forming part of Letters Patent No. 394,259, dated December 11, 1888.

Application filed May 16, 1888. Serial No. 274,105. (No model.)

To all whom it may concern:

Be it known that I, JAMES C. FRENCH, of Brooklyn, in the county of Kings and State of New York, have invented a new and useful Improvement in Devices for Operating Trap-Doors, of which the following is a specification.

This invention relates to endless screws applied to trap-door frames in gear with curved toothed racks attached to the doors.

I will proceed to describe such a trap-door operating device embodying my improvement, and afterward point out the novelty in claims.

In the accompanying drawings, Figure 1 represents a vertical section of a trap-door, a part of the frame thereof, and shows applied thereto a device embodying my invention. Fig. 2 is a sectional view, taken at right angles to Fig. 1, of a part of the trap-door frame and of the device for operating the door. Fig. 3 is a plan view of the device which constitutes the principal feature of my invention, and Fig. 4 is a perspective view of the rod for turning the endless screw.

Similar letters of reference designate corresponding parts in all the figures.

A designates the trap-door frame; B, the trap-door; C, the toothed rack attached to the trap-door, and D the endless screw, gearing with the said rack, for opening and closing the door.

E designates the hanger in which the endless screw D is supported. This hanger consists of an open frame closed at the bottom but open at the top and furnished on opposite sides with two lugs, e, through which it is bolted to the trap-door frame A by bolts a. In the bottom of this hanger is the bearing for the lower journal, d, of the endless screw

D, the upper journal, d', of which has its bearing in a removable cap-plate, D', which is fitted into a seat in the open top of the hanger.

This seat is shown at b in Fig. 1 as tapered vertically, and is shown at c c in Fig. 3 as having recesses in its sides to receive projections c, provided on the sides of the hanger, the said projections and recesses serving to keep the said cap-plate from passing out laterally from the hanger, while the taper sides b b of the seat serve to support the said plate vertically.

When the cap-plate D' is in the seat in the hanger, its upper surface is flush with the top of the hanger, and when the hanger is bolted into its place by the bolts A the cap-plate D' is thereby secured in place without further fastening. The cap-plate is, as shown in Figs. 2 and 3, wider than the hanger, so that the portion d², which contains a slot, d³, which receives the rack and confines it to the endless screw, projects beyond the inner edge, a', (see Fig. 2,) of the frame A.

The removable cap-plate provides for the convenient insertion of an endless screw having its journals integral with it, the cap-plate being removed to drop the screw into the yoke from above and being afterward replaced to receive the upper journal of the screw and confine the screw in an upward direction.

The lower journal, d, of the endless screw projects down some distance through the hanger, and has provided near its lower end two lugs, f, on opposite sides, for the reception of the bifurcated hook g; provided on the upper end of the rod F, Figs. 1 and 4, the lower end of which is furnished with a crank, h. This rod, which may be laid aside when not required for use, may be of any length, so that by it a man standing on the bottom of a deep cellar or vault may reach the screw for the purpose of turning it to operate the trap-door at the mouth of said cellar or vault.

In order to provide for the insertion of the lower journal, which is provided with lugs, through the bottom of the hanger E, the journal-bearing in the bottom of said hanger is provided with a notch on each side, as indicated at d⁴ in dotted lines in Fig. 1.

What I claim as my invention, and desire to secure by Letters Patent, is—

1. The combination, with a trap-door frame and an endless screw applied thereto for operating a rack on the trap-door, of the hanger having an open top and laterally-projecting lugs and containing the bearing for the lower journal of said screw, and a removable flush cap-plate containing the bearing for the upper journal of the screw and fitting to a seat in the open top of the hanger, substantially as described, whereby the bolting of the hanger to the under side of the frame is made to secure the cap-plate in the hanger and hold the

- screw in place therein, as hereinbefore set forth.
2. The combination, with the endless screw D, the rack C, gearing therewith, and the open- 5 topped hanger E, containing the bearing for the lower journal of the endless screw, of the removable flush cap-plate D', containing the bearing for the upper journal of the endless screw, and having a slotted projection, d^2 d^3 , 10 projecting laterally beyond the hanger, for the purpose of receiving the rack and confining it to the screw, substantially as herein described.
3. The combination, with the hanger E and an endless screw, D, having its lower journal, d , extending through said hanger and pro- 15 vided with lugs f on opposite sides, of the rod F, having a bifurcated hook on its upper end and a crank on its lower end, substantially as and for the purpose herein described.

JAMES C. FRENCH.
